WILBUR H. ARMACOST,
INVENTOR.

BY

O. V. Thiele

ATTORNEY.

UNITED STATES PATENT OFFICE

WILBUR H. ARMACOST, OF NEW YORK, N. Y., ASSIGNOR TO THE SUPERHEATER COMPANY, OF NEW YORK, N. Y.

HEADER FOR WATER-TUBE BOILERS

Application filed January 23, 1928. Serial No. 248,701.

This invention relates to boilers of the so-called horizontal water-tube type and is particularly concerned with the means for supporting the sectional headers into which the 5 ends of the water-tubes are expanded. The purpose of the invention is to provide novel means for supporting such headers.

The invention is illustrated in the drawing accompanying this specification, in which 10 drawings Fig. 1 shows a lateral view of a portion of one of these headers with the attached tubes and the novel supporting means; Fig. 2 shows a sectional view on line 2—2 of Fig. 1; Fig. 3 is a section on line 3—3 of Fig. 2; 15 Figs. 4, 5 and 6 are top views similar to Fig. 2 showing modifications, each showing portions also of the adjacent headers; and Fig. 7 is a section on line 7—7 of Fig. 6.

It will be understood that the water tubes 20 1—1 which are shown with one end secured into the header 2 have their other ends similarly connected to a corresponding header and that there is a series of such headers at each end arranged side by side. All of this is 25 according to the ordinary arrangement.

By means of my invention it is feasible to use ordinary tubing circular in cross-section for these headers. The lower ends of the headers are closed in any desired manner. 30 To close the upper end, a partition 3 is welded in, some distance below the top 4 of the header 2. If desired, reinforcement can be added by oxyacetylene welding at 5. The tubes 1—1 are rolled in in the ordinary manner, the necessary hand-holes for this purpose (not shown) being provided opposite their ends.

To support each of these headers a rod or bolt 6 is secured in the upper open end 40 which is engaged by the hanger 7. The upper end of this hanger is supported in any desired manner on the supporting I-beams 8—8 or other stationary members. In the form shown, the hanger 7 passes through a plate 9 resting on the I-beams, its upper threaded end having on it the nut 10.

In the form illustrated, two circulating 45 pipes 11 and 12 open into the upper end of the header. The tube 11 is rolled in in the ordinary way through the hand-hole 13. 12

is shown as secured in the partition 3. The tool for rolling it in is also inserted through the hand-hole 13. To allow the tube 12 to be bent toward the drum with which it is to communicate without interfering with the 55 bolt 6, the wall of the open end is cut away as at 14.

It will be evident that in the arrangement as described the projecting ends of the bolts 6 prevent placing the headers in close contact with each other. This may at times be objectionable, and the forms of the invention shown in Figs. 5 to 7 obviate it.

In Fig. 4 the outer ends of the holes through which the bolt 6 extends are slightly 60 countersunk and the ends of the bolt are expanded to fill the counterbore as at 6a—6a. This permits placing the headers in contact with each other.

In the form of Fig. 5 the bolts 6 are allowed to project as in the form first described, but they are each placed at such an angle that the projecting ends do not interfere with the adjacent headers.

Figs. 6 and 7 illustrate a form in which 70 the ends of the rod 6 do not extend through the walls but lie in opposite recesses in the interior of the walls. The shape of the recesses and the method of inserting the rod will be clear from an inspection of the figure. 80

While I have shown and described some specific forms of my invention, it will be obvious that variations can be made in practice without losing the spirit of the invention. Thus it will be clear that the invention has 85 particular utility when headers of circular cross-section are used, but it is not limited to headers of this form. Headers which are rectangular in cross-section can have my invention applied to them. This and other variations are intended to be within the scope 90 of my claims.

I claim:

1. In a header of the class described having a closed upper end, the means of support comprising an extension of the walls of the header upward beyond the closure of the upper end, a bar engaging said extension at two opposite points, a fixed support above the 95 100

header, and a hanger engaging the bar and the support.

5 2. In a cylindrical header of the class described having a closed upper end, the means of support comprising an extension of the header walls beyond the closure of the upper end, said extension being perforated at two diametrically opposite points, a fixed support above the header, a bar engaging the two perforations, and a hanger engaging the bar and the support.

10 3. In apparatus of the class described, the combination of a vertical row of boiler tubes, a header to which one end of each is secured, 15 an apertured closure for said header below the upper end of its wall, means to support the header comprising a fixed support above the header and suspension means engaging the support and the header wall above the 20 closure, and a circulator tube one end of which is secured in said aperture.

25 4. In apparatus of the class described, the combination of a vertical row of boiler tubes, a header to which one end of each is secured, 30 an apertured closure for said header below the upper end of its wall, means to support the header comprising a fixed support above the header and suspension means engaging the support and the header wall above the 35 closure, and a circulator tube one end of which is secured in said aperture, said header wall above the closure being cut away at one side and said circulator tube extending through the space so formed and its end being bent toward the closure.

WILBUR H. ARMACOST.
